HENRY I. LEA, OF PITTSBURG, PENNSYLVANIA.

GAS MANUFACTURE.

No. 873,250.

Specification of Letters Patent.

Patented Dec. 10, 1907.

Application filed July 24, 1905. Serial No. 270,912.

To all whom it may concern:

Be it known that I, HENRY I. LEA, a citizen of the United States, and a resident of Pittsburg, in the county of Allegheny and 5 State of Pennsylvania, have invented a new and useful Improvement in Gas Manufacture, of which the following is a specification.

This invention relates to the manufacture of gas and more particularly to a process by 10 which a gas of a character suitable for general distribution throughout cities may be produced at lower cost per unit of heat than present methods allow.

At present the manufactured gas supplied 15 to cities is made from one or more of the following processes: retort coal gas works, by-product coke ovens, carbureted water gas plants, (which include crude oil water gas plants), acetylene gas plants and plants distributing air laden with vapor from petroleum 20 distillate, such as gasoline. While each of these processes may be made to yield a gas or vapor of satisfactory thermal value for many requirements, the cost of manufacture (be- 25 cause of thermal losses and high cost of raw material), is such as to very greatly restrict the application of these gases to heating and other industrial requirements. On the other hand, producer gas, as such, is manufactured 30 at an exceptionally low cost per unit of heat, but its bulk is such as to render prohibitive its distribution for city supply. Furthermore, there are many industrial uses for gas which require higher flame temperature than 35 producer gas alone will develop.

An object of this invention is, therefore, to provide a process for the manufacture of gas of higher thermal value per cubic foot than ordinary producer gas, yet having a lower 40 cost per B. T. U. than any of the gases now manufactured for city supply.

The single sheet of drawing accompanying 45 this application illustrates one style of apparatus in which may be performed the successive steps comprising the process of gas manufacture herein set forth.

Figure 1 is a plan view of the apparatus. Fig. 2 is a sectional elevation of Fig. 1.

For the sake of clearness a brief description 50 of the details of the apparatus illustrated will be given in connection with the successive steps embodied in my invention, although I expressly do not limit myself to the specific arrangement or construction illustrated.

In a gas generating chamber 3 the pro-

ducer gas forming the basis of this process is manufactured. This generating chamber or producer proper may be provided with a suitable fuel feeding device 4. The design of 60 this device may be such as to allow of either hand or power operation either intermittently or continuously. The lower edge of the shell of this generating chamber dips into a water seal 6 through which the ashes re- 65 sulting from the combustion of fuel in chamber 3 may be removed without affecting the continuous manufacture of producer gas.

The generating chamber 3 may be provided with blast pipe 7 and with revolving 70 table 5, or with other suitable device allowing of the admission of blast to the fuel bed through a layer of ash and providing for the support of the fuel bed. Connected with the blast pipe 7 may be a steam-jet-blower 8 of the 75 commonly known injector type, or any other arrangement for admitting to blast pipe or twyer 7 an admixture of steam and air capable of adjustment, so that the gas leaving the fuel bed may have the desired characteris- 80 tics, even though the nature of the fuel be changed. The air supplied to this blower may or may not be preheated, although with the arrangement here shown a slight advantage will obtain through the preheating of the 85 air supplied to blower. In the style of apparatus here shown, a blower 8 receives its steam through pipe 9 from the steam space of boiler 24, the steam entering the blower being controlled manually by a valve in pipe 9. If 90 it were desired to make gas at varying rates with this apparatus to meet variable conditions of demand, a supply of steam through pipe 9 and of air through pipe 10 would be controlled automatically, the respective vol- 95 umes being determined by the gas pressure at the outlet of the apparatus.

The gas outlet 11 from chamber 3 connects with a checker-brick chamber 12 which is provided with a spraying device 13 connected 100 to a supply of oil or tar, or other carbureting liquid and to the steam pipe 9 by the valved pipe 14. This chamber 12 is made like the carburetor of an ordinary Lowe water gas apparatus and is provided with a valved air 105 supply pipe 15 connected to the air pipe 10. The bottom portion of this checker-brick chamber is connected with a second checker-brick chamber 17 by a passage 16, which is provided with a valved air supply pipe 18 also 110 connected with air pipe 10. The checker brick chamber 17 is divided into two parts by a ver-

tical heat-resisting partition 19 and is provided with a valved air supply 20 also connected with the air pipe 10. Attached to the bottom of the shell of chamber 17 and on the gas outlet side is a gas passage leading to stack 43, which is provided with valve 44 which is to conduct the gases from the checker brick chamber to the atmosphere when first starting this apparatus in operation.

10 The air pipe 10 is connected to a blower 21, which is operated by power from any suitable source such as a pulley 22. This blower 21 obtains its air from the atmosphere, or as here shown, from the annulus between the 15 jacket and the shell of the washing or cooling chamber 35, in which case the air will have absorbed some of the heat radiated from the shell 35, this heat then being returned to the fuel bed through the blast pipe 7, and to the 20 carbureting chambers through pipes 15, 18 or 20.

At the bottom of chamber 17 and opposite the gas inlet 16 is a gas outlet 23 leading to dust chamber 26 formed by shell 24. This 25 shell also forms part of tubular boiler 25, mounted over the chamber 26, the lower portion of which is provided with a fuel grate 27, which may be dumped into a pipe leading to a water bottom 28. The tubes of the boiler 30 25 lead the gases from chamber 26 to chamber 29 from which the gases leave through passage 30 and valve 34 to the cooling chamber 35 or through valve 32 and pipe 31 to the atmosphere. The gas inlet 23 to chamber 26 35 is provided with valve 33. The gas passage 30 connects chamber 29 with the washing and cooling chamber 35, which is provided with cold water sprays 36 connected with city or other suitable supply. From this same supply 40 the water for boiler 24 may be obtained. The chamber 35 is provided with a hanging baffle plate, causing the gas to travel from inlet passage 30 through the sprays to the bottom of chamber 35 then through the remaining 45 sprays to the top of the chamber 35 where outlet passage 37 connects with the combined scrubber and drier 38. The chamber 35 is provided with a jacket through which the air entering blower 21 is drawn as previously explained. The scrubber 38 is provided with a 50 chamber 39 which may be filled with coke or other suitable gas scrubbing material and a drying chamber 40 filled with excelsior or other suitable drying material. These two 55 chambers are connected by a washing chamber 41, which collects the water coming from the water sprays in the scrubbing chamber. From chamber 41 this water overflows through a seal pot to the sewer, or other 60 drain system. The gas leaving chamber 39 bubbles through the water in chamber 41 before entering chamber 40. The water supply to the sprays in chamber 39 may come from the same source as that for the sprays in 65 chamber 35. Chamber 40 is provided with a

gas outlet 42 which may be connected to the apparatus for the removal of surplus compounds if this be necessary, or to a gas holder, or directly to the distributing system.

The operation of the apparatus is as follows: The boiler 24 having been filled with water to a point above the upper tube sheet, a fire is started on the grate 27 in chamber 26, the valves 33 and 34 now being closed and valve 32 opened. The air required for combustion of fuel on this grate enters through a door below the grate, (this door not shown), and the fuel, (which would be wood, coal or coke), is supplied to the grate through a door above the grate and below the boiler tubes 80 25. A fire having been started and this last mentioned door having been closed, the products of combustion pass through the tubes of boiler 24, through the chamber 29; valve 32 and pipe 31 to the atmosphere. 85 This fire is maintained until the water in boiler 24 is heated and a suitable steam head developed. Steam pipe 9 connected with the blower 8 is then opened as is air pipe 10. The belt or other device driving blower 21 is 90 now thrown into commission and air is drawn through the holes in the bottom of the jacket surrounding cooling chamber 35 and then into the blower, and out of the blower into pipe 10 to the steam-jet-blower 8. From 95 blower 8 a mixture of steam and air passes through twyer 7 into and through the fuel bed which has previously been provided with a layer of ash on the table 5 extending above the twyer 7 and by having wood, old 100 waste, etc., followed by a little coke and soft coal placed on this ash bed. The ashes and this material for starting the fire may be introduced through a door in the shell of the producer just above the twyer, or through 105 the feeding device 4, or through the poke holes arranged around this feeding device in the head of the producer shell, (neither this door nor the poke holes are shown). The poke holes in the top of the producer shell 110 are now all left open and this old waste, etc. is ignited by means of a lighted torch introduced through last mentioned door, which is then bricked up and closed. The door in the producer shell below the ash bed is open to 115 allow of natural draft through the ash bed and through the small fire bed up through the poke holes into the atmosphere. As soon as this small fire bed has been well established and more coal added, the door in 120 the producer shell below the ash bed is closed and the steam blower 8, provided with steam and air as before explained, is put into commission. The blast now leaving the twyer 7 passes through a portion of the ash bed, then 125 through the fuel bed and out through the poke holes in the top of producer shell. The fire on grate 27 is in the meantime maintained to provide the steam required for the blower 8 until the fuel bed in chamber 3 is of 130

sufficient depth to allow of a relatively strong blast being applied. When this condition has been developed in the fuel bed, the poke holes in the top of producer shell are closed.

5 Valve 44 in waste stack 43 is opened. Now, the gas leaving the fuel bed in chamber 3 passes from the fuel bed through gas passage 11, around and over the checker-brick in chamber 12, through gas passage 16, around 10 and over the checker-brick in chamber 17 and from the bottom of chamber 17 through the valve 44 and waste stack 43 to the atmosphere. In this passage a large portion of the sensible heat of these gases is absorbed by the checker-brick. To facilitate the bringing about of the required temperature in the checker-brick chambers, air is now admitted to chamber 12 by opening valve 15, and to chamber 17 by opening 15 valves 18 and 20. This admission of air in proper quantities will consume the producer gas coming over the fuel bed to such extent as may be desired, the products of combustion and remaining unburned gases, if any, 20 all escaping through the waste stack 43 to the atmosphere until the fuel bed has been brought up to its normal working condition and until the checker-brick chambers have attained the temperature at which it is desired to operate. Having now attained the 25 temperature desired throughout the first three portions of the apparatus and having still a satisfactory steam head in the boiler 24 the valve 32 in stack 31 is closed, thereby 30 preventing the escape of the products of combustion coming up from the fire on grate 27. The door through which air was supplied below the grate for the maintenance of this grate fire is now closed and whatever 35 oxygen is now left within the shell is very rapidly combined with the carbon in the fuel bed on the grate. The grate 27 is now tipped into a vertical position by means of a crank connected with its bearing shaft, 40 which crank is located outside of the shell, and the fuel is dropped into the water bottom 28. There now remains in the chamber 26 and the chamber 29 and within the boiler tubes 25 practically no oxygen, and, therefore, 45 an explosion on the admission of gas from chamber 17 is practically impossible. At the worst this explosion would be very slight and would be amply cared for by the water seal 28. Valve 44 in waste stack 43 is, 50 therefore, now closed, while valves 33 and 34 are opened. The producer gas and the products of combustion now leaving chamber 17 pass into chamber 26 through the boiler tubes 25, through chamber 29, through passage 30 and valve 34 into the spraying or cooling chamber 35 to the bottom of this chamber, then up to passage 37 into scrubbing chamber 39, then through washer 41, then through drying chamber 40 to gas 55 outlet 42, from which, as before explained,

the gases would go to apparatus for the removal of sulfur compounds, or to a gas-holder, or to the distribution system direct. The gas now leaving outlet 42 is, of course, very poor, containing excessive quantities of CO₂. 60 The sprays 36 in chamber 35 and the sprays in the top of chamber 39 are now placed in operation. All the dust and vapors carried forward by the gases from passage 30 are now removed in chambers 35 and 38. The 65 gases on leaving chamber 17 through passage 23 contain considerable sensible heat, which is largely given up to the water in boiler 24 on the passage of the gases through tubes 25. In this way such quantities of steam are 70 maintained as may be required for the operation of steam-jet-blower 8 and no other steam supply need be maintained, unless local conditions render it advisable. The heat required for the maintenance of proper temperatures throughout the checker-brick and for raising of steam will be supplied by the sensible heat of the gas coming through passage 11 and the heat of combustion of a small portion of this gas, which will be effected by 75 the admission of air, as before explained, through valves 15, 18 and 20, but in much smaller quantities than required in first starting the apparatus. Now, to bring up the 80 thermal value of the gas leaving the apparatus at outlet 42, a hydro-carbon liquid, (either crude oil, or some distillate of crude oil, or some form of tar, or distillate of tar, or other suitable hydro-carbon liquid), is admitted through sprays 13 into chamber 12, 85 this enricher having been supplied through the pipe marked "Oil," which is connected to a suitable pump which delivers the enriching material under a constant head to the sprays 13. The volume of this enricher admitted to sprays 13 will be determined by adjusting a valve on the oil line. If it be desired to use no pump, the oil line would be led to an injector into which steam would be admitted through valve 14, and the steam on 90 passing through this injector would entrain the oil and spray it in the chamber 12 in the form of a mist. The pump system is preferable, but the injector system is here shown for simplicity. The hydro-carbon mist leaving the sprays 13 now mixes mechanically with the producer gases coming through passage 11, which gases are at a high temperature and with these gases passes around and over the highly heated checker-brick in the 95 chambers 12 and 17, in which passage the hydro-carbon vapors are gasified and cracked up into permanent gases. These hydro-carbon gases being now intimately mixed with the producer gas and with the products of 100 combustion developed by the admission of secondary air in such quantities as may be required for the maintenance of proper temperatures in the checker-brick, will now pass through the boiler, thereby giving up a large 105

110

115

120

125

130

portion of their sensible heat for the maintenance of steam, then through the spray chamber 35, where the gases will be cooled and freed from a large portion of such vapors and dust as may be carried forward, then to scrubber 39 where the remaining vapors will be condensed, then to the washer 41 where the remaining dust particles will be removed, then to the chamber 40 where practically all of the water vapor will be collected and dropped back into the washer 41, then through outlet 42. Now, having this apparatus in full operation, the thermal value of the gas leaving outlet 42 may be increased or diminished by changing the volume of enricher admitted per volume of producer gas. The sensible heat carried forward in the producer gas leaving the fuel bed may be altered at will by changing the CO_2 content in such producer gas, which change, assuming constant conditions to obtain in the fuel bed, would be brought about by changing the ratio of steam to air in the blast of blower 8. It is obvious that the sensible heat alone in the producer gas entering chamber 12 would be sufficient to vaporize certain enrichers in certain quantities and still leave sensible heat enough for the development of steam in boiler 24, but additional heat will be required in handling the heavier oils, particularly the tars, when adding the quantity of enricher that would be found desirable in practice. This arrangement, therefore, allows of great elasticity, as a producer gas of say 130 B. T. U.'s may easily be enriched to a point where the resulting gas would have from 200 to 300 B. T. U.'s or even more per cubic foot.

I do not wish to restrict myself in any way to any particular thermal value, as this will be determined by the requirements locally. It is obvious that even the crude type of gas producers now used, (for instance in connection with open hearth furnaces in the manufacture of producer gas from very cheap bituminous coals), might be used in connection with the carbureting arrangement I have shown, inasmuch as the tarry vapors now considered a nuisance would be carried directly in the carbureting chamber where these same tarry vapors would be dissociated and fixed into permanent gases in the same way as would the other enricher added. It is, therefore, not essential to the success of this process to have a producer that will make tar-free gas. Neither is it essential that enricher other than tarry vapors be added, for by the admission of a very small quantity of air such portions of the producer gas may be burned within the carbureters as will maintain the temperatures at such a point that the tarry vapors carried forward will be thereby dissociated and rendered fixed. The apparatus I have shown may, therefore, be applied to present styles of producers for the purpose of rendering this producer gas free of

tar by the process just outlined. The gas resulting from this operation would not be adapted to city supply because of its low thermal value, but would be adapted to many industrial requirements, including the driving of gas engines, etc. Without some device for the removal of the tarry vapors, the gas from bituminous coal producers now used for furnace work, etc. cannot be used in engines because of the sticking up of valves, etc.

I do not wish to restrict myself in any way to the use of the particular arrangement of apparatus herein described. The producer proper (chamber 3), may be of the form shown, or of any other form adapted to the manufacture of what is commercially known now as producer gas from any fuel or substance suitable for that purpose. The carbureters may be arranged as here shown, or in any other suitable way in one or more shells. The boiler may be of this, or any other suitable design, or may be omitted altogether, in which case the sensible heat now utilized in raising steam would be lost in the cooling and scrubbing apparatus and the steam would have to be supplied from an outside source. The coolers or scrubbers may be of this, or any other suitable design,—either stationary or rotary. The air may be heated as shown, or in any other part of the apparatus, or not at all. The enriching material may be applied as shown without pre-heating, or any suitable contrivance may be used in which the sensible heat of the gas itself may be taken advantage of in preheating the enriching material. The cooling and scrubbing apparatus may be omitted altogether in cases where hot gas containing some dust and some vapors may be used to advantage directly, as in furnace work. It is obvious that within practical limits the thermal value or the candle power of the gas made by this apparatus may be varied and that any apparatus utilizing to advantage the ideas involved in the apparatus here explained would be suitable for the manufacture of gas in central stations connected with distribution systems for conducting the gas over large territories.

Because of the low cost of manufacture of this gas and the ease with which its thermal value may be adjusted to meet local conditions, this gas will be commercially available for such domestic requirements as cooking, heating, lighting, and in industrial undertakings for the numberless duties to which natural gas, coal gas, water gas, oil gas, producer gas, acetylene gas, gasoline and other oil vapors, etc. are now applied.

In this apparatus is combined the results of design, construction and practical operation of coal gas, water gas, oil gas and producer gas plants and in this process there are no such thermal losses as occur in coal gas,

water gas, or oil gas manufacture as at present carried out, excepting the loss through radiation. Because of its elimination of avoidable thermal losses and of its adaptability to continuous operation, this apparatus will have a higher thermal efficiency than any process now or heretofore used in the manufacture of gas for city supply.

Having now described this invention what 10 I claim is:

1. The method of manufacturing gas which consists in passing air through a fuel bed in such quantities as to support only partial combustion, then in enriching the resultant 15 gas by introducing hydrocarbon oil into it, then in burning enough of said gas in the presence of said hydrocarbon oil so that the heat resulting from the combustion, together with the sensible heat of the gas, will be sufficient to break up the hydrocarbon oil into 20 vapors and fix said vapors into permanent gases which are mechanically mixed with the remainder of the gas, thereby producing a permanent gas of relatively high thermal 25 value.

2. The method of manufacturing gas which consists in passing air through a fuel bed in such quantities as to support only partial combustion, then enriching said gas by introducing an enricher into it, then burning a portion of the gas for fixing the enricher into permanent gases and allowing the products of combustion to mingle with the enriched 30 gas.

3. The method of manufacturing gas which consists in passing air through a fuel bed in such quantities as to support only partial combustion, passing said gas through a chamber, introducing carbonaceous material 40 into said chamber with said gas, burning a portion of said gas within said chamber so that the heat of combustion resulting therefrom, together with the sensible heat of the gas, will break up the carbonaceous material 45 into vapors, and fix the vapors into permanent gases which, together with the products of combustion, mix with the gas to produce a permanent gas of relatively high thermal value.

4. The method of manufacturing gas which consists in passing air through a fuel bed in sufficient quantities to support only partial combustion, then passing the gas resulting therefrom through a chamber, introducing 55 carbonaceous oil into said chamber with said

gas, burning a portion of the gas within said chamber so that the heat of combustion resulting therefrom will break up the carbonaceous material into vapors and fix the vapors into permanent gases which, together with the products of combustion, mix with the gas to produce a permanent gas of high thermal value.

5. The method of manufacturing gas which consists in generating producer gas, passing 60 said gas through a chamber, introducing an enricher into said chamber and maintaining a fixing temperature within said chamber by admitting air thereto and thereby burning a portion of said gas within said chamber.

6. The method of manufacturing gas which consists in generating producer gas, passing said gas through an enricher chamber, introducing air into said chamber for the purpose of burning a portion of said gas within said 70 chamber and thereby maintaining a fixing temperature.

7. The method of manufacturing gas which consists in generating a gas of relatively low thermal value, then in enriching the resultant gas by introducing carbonaceous material into it, then in burning a portion of said gas in the presence of said material so that the heat resulting from the combustion, together with the sensible heat of the generated gas, will be sufficient to break up the said material into vapors and gases which, together with the products of combustion, are mixed with the gas to produce a gas of relatively high thermal value.

8. The method of manufacturing gas which consists in generating a gas of relatively low thermal value, passing said gas through a fixing chamber, introducing an enricher into said chamber, burning a portion of the gas in the presence of said enricher for the purpose of maintaining a proper temperature within said chamber to dissociate said enricher into vapors and permanent gases which, together with the products of combustion, are mechanically mixed with the remainder of the gas to produce a gas of relatively high thermal value.

In testimony whereof, I have hereunto subscribed my name this 21st day of July, 1905.

HENRY I. LEA.
